UNITED STATES PATENT OFFICE.

ROBERT KELLER, OF ENNETBADEN, SWITZERLAND, ASSIGNOR TO AKTIENGESELLSCHAFT BROWN BOVERI AND CIE, OF BADEN, SWITZERLAND.

PROTECTIVE DEVICE FOR USE IN POLYPHASE-CURRENT INSTALLATIONS.

Application filed November 3, 1925, Serial No. 66,617, and in Germany November 17, 1924.

This invention has reference to protective devices for use in polyphase current installations designed to become operative when an overload occurs on one or more of the 5 phases.

It is known, in polyphase current installations, to use a regulator as a protection against overload, the regulator coming into operation when a certain load has been attained and reducing the exciting current of the generators supplying the installation, so that the output is reduced to normal. In polyphase current installations however there is a disadvantage in that the effect of 10 the overload on the regulator varies according to the nature of the overload, i. e., whether it occurs on one, two or all the phases.

This disadvantage is overcome by the present invention which ensures that the regulator shall operate whether the current exceed the limit in one, two or all the phases and whether the currents be leading, lagging or in phase. The object of the invention 15 is attained by providing as many electrically separate magnetic devices as there are phases, each of the devices acting independently on the control member of the regulator.

Forms of the invention will now be described with reference to the accompanying drawings wherein:—

Fig. 1 shows diagrammatically one embodiment of the invention, and

Fig. 2 shows diagrammatically a second form of the invention.

Figures 3 and 4 illustrate diagrammatically two further embodiments of the invention.

In the embodiment of the invention diagrammatically illustrated in Fig. 1 a is a resistance inserted in the field circuit of the exciter c of the polyphase generator b. This resistance is controlled by a member d which normally occupies a position in which the resistance a is short circuited thereby. The member d is held in the position mentioned by a spring f. The member d carries a plate e which occupies a position opposite to, but separate from, the armature of an electromagnet g and the ends of two two-armed levers m, n. The levers m, n are connected with and operated by the armatures of electromagnets h, i, respectively. k, k, k are tension springs which act

on the armatures of the electromagnets g, h, i and oppose their movement. Each of the windings of the electromagnets g, h, i is connected through an independent current transformer o with one of the leads 60 R, S, T.

The operation of the device is as follows:—

If, for example, an overload occurs in one of the phases, say, in phase S, the electromagnet i is energized to actuate the lever m which strikes and raises the plate e and with it the member d. The short circuit on the resistance a is removed, wholly or partly, the exciting current is reduced and the 65 potential of the generator b falls. In the case of an overload of equal amount in two or all the phases, the electromagnets energized by the said phases are caused to operate the member d. In order that the 70 pressure on the plate e may be kept practically equal in the case of an overload on one, two or all the phases the spring f is made as weak as possible in relation to the pull of the electromagnets g, h, i. 80

Fig. 2 illustrates diagrammatically another embodiment of the invention in which the electromagnets g, h, i, act on Ferraris discs p. The discs p are also influenced by springs k which normally hold them against a stop q. Now if the current, for example, in phase R exceeds the predetermined limit, the disc p rotates, together with a toothed segment r, against the pull of the spring k in the direction indicated by the arrow. The 85 toothed segment r meshes with a toothed wheel s loosely mounted on the shaft e of the regulator. When the toothed wheel s has rotated through a predetermined angle, a pin t mounted on the toothed wheel s 90 comes in contact with a lever u mounted on the shaft e of the regulator. The shaft of the regulator is connected with a contact segment d and this contact segment d is 95 operated and is moved in a direction to insert resistance a into the field circuit of the exciter when the lever u is acted on by the pin t.

Referring to Figs. 3 and 4, when an overload occurs on one, two or all of the phases, 105 a switch v is operated by the electromagnet or electromagnets that is or are energized to actuate. The switch v controls the circuit of the regulator w. In the embodiment illustrated in Fig. 3, when an 110

overload occurs on one or more of the phases, the armature of one or more of the electromagnets *g*, *h*, *i*, strikes the switch plate *f* and closes switch *v*. The closing of switch *v* places the vibrator coil of the Tyrrill Regulator *w* in circuit and the field current of the exciter is weakened.

In the embodiment illustrated in Fig. 4, the switch *v* is opened on an overload by 10 at least one of the electromagnets *g*, *h*, *i*, and the holding-on coil *v* of the switch arm *x* is de-energized. The switch arm *x* is released and as it moves resistance *a* is inserted into the field circuit of the exciter.

15 The devices shown act equally well on single phase circuit as on a two-phase or a three-phase circuit.

What I claim is:—

1. Means for controlling overloads in 20 polyphase installations comprising a single regulating member to control the current supplied by the generator, a plurality of electrically separate electromagnetic devices connected one in each phase and an operative connection between each electromagnetic device and the regulating member.

2. Means for controlling overloads in 30 polyphase installations comprising a single regulating member to control the current supplied by the generator, a plurality of electrically separate electromagnetic devices, a plurality of current transformers connected one in each phase with each secondary connected to a separate electromagnetic device, and an operative connection 35 between each electromagnetic device and the regulating member.

3. Means for controlling overloads in 40 polyphase installations comprising a single regulating member to control the current supplied by the generator, a plurality of electrically separate electromagnetic devices one connected in each phase and each controlled by a separate spring and an operative connection between each electromagnetic device and the regulating member.

4. Means for controlling overloads in 50 polyphase installations comprising a single regulating member to control the current supplied by the generator, a plurality of electrically separate electromagnetic devices each controlled by a separate spring, a plurality of current transformers connected one in each phase with each secondary connected to a separate electromagnetic device and an operative connection between each electromagnetic device and the regulating member.

5. Means for controlling overloads in 60 polyphase installations comprising a single regulating member to control the current supplied by the generator, a plurality of electrically separate electromagnetic devices connected one in each phase, and an operative connection between each electromagnetic device and the regulating member.

netic device and the regulating member having a time lag between the commencement of operation of the electromagnetic device and its action on the regulating member.

6. Means for controlling overloads in 70 polyphase installations comprising a single regulating member to control the current supplied by the generator, a plurality of electrically separate electromagnetic devices, a plurality of current transformers 75 connected one in each phase with each secondary connected to a separate electromagnetic device, and an operative connection between each electromagnetic device and the regulating member having a time lag between the commencement of operation of the electromagnetic device and its action on the regulating member.

7. Means for controlling overloads in 80 polyphase installations comprising a resistance connected in the field circuit of the exciter of the polyphase generator, means to vary the amount of said resistance connected in the circuit, a plurality of electrically separate electromagnetic devices 90 connected one in each phase of the polyphase installation, and an operative connection between each electromagnetic device and the means to vary the amount of the resistance connected in the circuit.

8. Means for controlling overloads in 95 polyphase installations comprising a resistance connected in the field circuit of the exciter of the polyphase generator, means to vary the amount of said resistance connected in the circuit, a plurality of electrically separate electromagnetic devices, a plurality of current transformers connected one in each phase with each secondary connected to a separate electromagnetic device and an operative connection between each electromagnetic device and the means to vary the amount of the resistance connected in the circuit.

9. Means for controlling overloads in 110 polyphase installations comprising a resistance connected in the field circuit of the exciter of the polyphase generator, means to vary the amount of said resistance connected in the circuit, a plurality of electrically 115 separate electromagnetic devices connected one in each phase of the polyphase installation, and an operative connection between each electromagnetic device and the means to vary the amount of the resistance having a time lag between the commencement of operation of the electromagnetic device and its action on the means to vary the amount of the resistance.

10. Means for controlling overloads in 125 polyphase installations comprising a resistance connected in the field circuit of the exciter of the polyphase generator, means to vary the amount of said resistance connected in the circuit, a plurality of electrically 130

- separate electromagnetic devices, a plurality of current transformers connected one in each phase with each secondary connected to a separate electromagnetic device, and 5 an operative connection between each electromagnetic device and the means to vary the amount of the resistance having a time lag between the commencement of operation of the electromagnetic device and its 10 action on the means to vary the amount of the resistance.
11. The combination with a polyphase generator having a field winding of a regulator for controlling the current in said field winding to maintain predetermined operating conditions in said generator, said regulator comprising means individual to each of the phases of the generator dependent only on the conditions in the respective phases, and a field-current control means common 20 to all phases and actuated individually or in common by said means.
12. The combination as defined in claim 11 characterized by the means individual to each of the phases of the generator comprising current transformers.

Dated this 9th day of October, 1925.

ROBERT KELLER.
